UNITED STATES PATENT OFFICE.

ABRAHAM FRAHAT HADDAD, OF FERNIE, BRITISH COLUMBIA, CANADA, ASSIGNOR
TO ROSIE HADDAD, OF CRANBROOK, BRITISH COLUMBIA.

DIRECTION INDICATOR.

Application filed July 30, 1923. Serial No. 654,714.

The present invention appertains generally to improvements in direction indicators for motor vehicles and specifically to a side indicator, as described in the present specification and illustrated in the accompanying drawings.

The invention consists essentially of the novel features pointed out broadly and specifically in the claims for novelty following a description containing an explanation in detail of an acceptable form of the invention.

The primary object of my invention is to provide a motor actuated signal of the character stated including an extendible signal arrow adapted to be automatically extended from and reected in its supporting casing.

Another object of the invention is to provide such a mechanism in a very compact and symmetrical structure, so that but very little space is occupied thereby on the windshield of the motor vehicle.

A still further object of the invention resides in the provision of an indicator embodying the aforesaid functional characteristics including a hollow arrowhead to which flexible side members are fastened, the latter being wound upon rollers positioned within a casing and adapted to extend with said arrowhead to form an indicating arrow.

In connection with the foregoing, the invention is further characterized in that means are provided co-operating said motor with said hollow arrowhead and flexible side members to extend the same when the motor is energized until the arrow in its entirety has reached its outermost position and automatically recede the same when the electrical motor circuit has been broken.

With the foregoing and other objects in view which will appear more fully as the description proceeds, the invention resides in the novel combination and arrangement or co-operating elements as hereinafter more specifically set forth, claimed and shown in the accompanying drawings forming a part of the present application, and in which:

Fig. 1 is an elevation illustrating a direction indicator constructed in accordance with an acceptable embodiment of my present invention, mounted upon the windshield of a motor vehicle.

Fig. 2 is an enlarged vertical transverse section through the casing of the indicator

illustrating the association of the different parts.

Fig. 3 is a vertical section taken substantially on the plane designated by the line 3—3 of Fig. 2 looking in the direction indicated by the arrows.

Fig. 4 is an enlarged horizontal section taken substantially on the plane designated by the line 4—4 of Fig. 2, looking in the direction indicated by the arrows.

Fig. 5 is a fragmentary detail illustrating the construction of the normally closed doors for the casing of the indicator, and

Fig. 6 is a longitudinal sectional elevation of one of the flexible side member supporting rollers.

Like numerals of reference designate corresponding components throughout the several views.

The numeral 12 indicates a rod which extends through a casing designated in its entirety by the numeral 13, said casing being clamped on the uprights of the windshield frame 14 of the motor vehicle 15, by means of clamping brackets 16 secured to said casing. The casing 13 has an extension 17 on its inner or rear side, in which the inner end of rod 12 operates. A covering 18 is provided for the casing 13 and its extension 17 and serves to complete the latter, as shown clearly in Fig. 3. A cap 19 is carried at the inner end of the rod 12 and one end of the extension spring 20 bears against the cap 19, while the other end thereof bears upon the extension 17 of the casing 13. This spring serves to resiliently retain the rod 12 in its innermost or reected position, as clearly indicated by the dotted lines in Fig. 3.

A rack 21 is formed in the rod 12, so that the rod 12 may be forced outwardly to extended position, as hereinafter described. A hollow arrowhead 23 is positioned on the outer end of the rod 12. A pair of flexible side members 24 are secured at their outer ends on the flat sides of the hollow arrowhead 23, while their inner ends are mounted upon spring rollers 25 within the casing 13. The said flexible side members may have the words "Right" and "Left" printed thereon so that the same will be disclosed when the indicating arrow in its entirety is extended.

The indicating arrow described extends through an opening 18^a provided for this purpose in the outer side of the casing 13

and its covering 18. A pair of doors 26 are provided to form a closure means for said opening 13^a and are provided with springs 27 to hold the same closed when the indicating arrow is positioned within the casing 13.

The rollers 25 are hollow and have springs 28 provided therein encircling the roller shafts 29. One end of the spring in each hollow roller 28 is connected thereto, while the other end of the spring is connected to the shaft 29. Each said roller shaft has a squared end 30 and the roller shafts 29 are mounted in the casing 13 on opposite sides in such a manner as to prevent rotation of the said roller shafts. It is, therefore, evident that when the flexible side members 24 are drawn outwardly during the outward movement of the rod 12, the springs 28 are wound up and serve to rewind said flexible side members 24 on the rollers 25 as the rod 12 is receded into the casing 13.

A pair of lamps 31 are carried on the transverse support 32 and the casing 13. The lamps 31 are surrounded by a reflector 33 having its open end directed towards the opening 13^a, the reflector being carried on the support 32. If desired, the hollow arrow head 23 may be made to form a like reflector adapted to oppose the reflector 33 to deflect the light against said flexible side members for illuminating purposes. Illumination of the flexible side members 24 occurs whenever a circuit is completed through the lamps 31, which are connected with the circuit wires 34 extending to the electric motor 35. The motor 35 is mounted in the casing so that the shaft 41 is parallel with the rollers 25. A gear 42 is positioned on the shaft 41 of the motor 35 and meshes with and drives the gear 43 rotatably mounted on the stub shaft 44. The gear 43 meshes with and drives the gear 45 which is loosely mounted on the roller shaft 29 of one of the rollers 25, and meshes with and drives gear 46 secured to shaft 47. Said shaft is rotatably carried in a support 48 extending at right-angles from the transverse bar 32. The shaft 47 has a spiral threaded portion 49 on which the pinion 50 operates.

When the motor 35 is energized, shaft 47 is driven through the gear mechanism described, and the pinion 50 is forced along the spiral thread 49 on said shaft 47 into engagement with the rack 21 on the rod 12 and extends said rod outwardly together with the hollow arrow head 23 to which the flexible side members 24 are connected.

When the circuit to the motor is broken, the spring 20 tensions the rod 12 inwardly and the springs 28 of the rollers 25 serve to rotate the shafts 29 of said rollers and

wind the flexible side members 24 thereon. As the rod 12 is receded, the pinion 50 is moved axially on the spiral threaded portion 49 of the shaft 47 until the same disengages the rod 12.

While the preferred embodiment of the invention has been described it is to be understood that minor changes in the details of construction, combination and arrangement of co-operating elements may be resorted to within the scope of what is claimed without departing from the spirit of the invention.

What I claim as new is:

1. A direction indicator of the character described including, in combination, an electric motor; a rod, provided with an arrowhead, geared to said motor adapted to be extended thereby; flexible side members adapted in connection with said arrowhead to form an indicating arrow, and adapted upon actuation of said rod, to extend and recede therewith; spring tensioned rollers to which said flexible members are connected and means for disengaging said indicating arrow mechanism from said electric motor when the same is receded from its full extended position.

2. A direction indicator of the character described including, in combination, an electric motor; a casing; a rod carrying an arrowhead, extendible from said casing; flexible members connected to said arrowhead adapted to form an indicating arrow in connection therewith; spring tensioned rollers within said casing to which said flexible members are connected; means for co-operating said motor with said indicating arrow mechanism to extend the same from said casing when said motor is energized; and means for receding said indicating mechanism after the same has extended a predetermined distance from said casing and the current to said motor is broken.

3. A direction indicator of the character described including, in combination, a casing; an electric motor positioned in said casing; a rod provided with a rack gear, extending through said casing; a drive pinion geared to said motor, mounted upon a shaft having a spiral thread, so that said pinion is receded from said rack gear when said rod is receded into said casing; a coil spring for returning said rod from its extended position; an arrowhead on said rod; flexible side members connected to said arrowhead, wound upon rollers positioned in said casing, adapted to move with said rod and arrowhead to form an indicating arrow in connection therewith.

In testimony whereof, I affix my signature.
ABRAHAM FRAHAT HADDAD.
